TELEDYNAMIC ORIENTATION SYSTEM.

1,420,629.

Specification of Letters Patent. Patented June 27, 1922.

Application filed March 29, 1918, Serial No. 225,523. Renewed August 5, 1921. Serial No. 490,111.

To all whom it may concern:

Be it known that I, JOHN HAYS HAMMOND, Jr., a citizen of the United States, residing in Gloucester, in the county of Essex and State of Massachusetts, have invented certain new and useful Improvements in Teledynamic Orientation Systems, of which the following is a specification.

Some of the objects of this invention are to provide an improved system for moving a body selectively through a predetermined and variable distance in response to radiant energy; to provide an improved system for the orientation of a rotatable body, such, for instance, as an aircraft, marine vessel, or other rotatable body selectively through a variable and predetermined arc in response to radiant energy, and then to steer said body automatically on a straight course; and to provide other improvements as will appear hereinafter.

In the accompanying drawings, Fig. 1 is a diagrammatic side elevation partly in section of a receiving system constructed in accordance with this invention and arranged to control a rudder of a marine vessel or other movable body; Fig. 2 is a top plan view of a detail of the same; Figs. 3 and 4 are a bottom plan view and a fragmentary end elevation of a second detail of the same; Fig. 5 is a top plan view of a portion of the same; Fig. 6 a sectional view on the line 6—6 of Fig. 5; Fig. 7 is a diagrammatic side elevation of a transmission system constructed in accordance with this invention; and Figs. 8 and 9 are a longitudinal section and a transverse section respectively of a detail of the same.

Referring to the drawings, and particularly to Figs. 1 to 6, one embodiment comprises a receiving system for radiant energy which is shown as arranged upon a movable body such, for instance, as a marine vessel, an aircraft or any other suitable movable body 19 provided with a propeller 20 arranged to be actuated by any suitable motor (not shown) for actuating the body, and with a rudder 25, under the control of the receiving system, for steering the body in any desired direction.

The rudder 25 is arranged to swing about an upright axis fixed with respect to the movable body or vessel upon a pivot 26, and for oscillating the rudder 25 a crank arm 27 is rigidly secured to the rudder and is arranged to be oscillated by a piston rod

28 which carries at its outer end a pin 29 which is arranged to slide in a slot 30 provided therefor in the arm 27. The inner end of the piston rod 28 extends slidably through 60 a stationary cylinder 35, and within the cylinder 35 is a piston 36 which is rigidly secured to the rod 28 and is normally held in a central position in the cylinder 35 by two spiral springs 37 and 38 arranged with 65 in the cylinder upon opposite sides respectively of the piston 36.

The piston 36 is arranged to be controlled pneumatically through the action of a valve 40 which includes a stationary valve casing 70 41 through which slidably extends a valve-stem 42 which has rigidly secured thereto two spaced pistons 43 and 44 which are arranged slidably within the valve casing 41. The central portion of the valve casing 41 is 75 connected by a supply pipe 45 to a tank 46 containing compressed air, and the valve casing 41 is connected by two pipes 47 and 48 to the opposite ends of the rudder cylinder 35, the outlets from the valve casing 41 into the 80 two pipes 47 and 48 being arranged upon opposite sides respectively of the supply pipe 45 and being normally closed by the pistons 43 and 44 which are held in suitable positions for this purpose by means of two oppositely 85 disposed spiral springs 50 and 51 which surround the valve-stem 42 and which are compressed respectively between the outer surfaces of the opposite ends of the valve casing 41 and two collars 52 and 53 which are 90 rigidly secured to the valve-stem 42. The valve casing 41 is provided at its opposite ends with two normally open exhaust ports or outlets 54 and 55.

For moving the valve-stem 42 in either direction selectively to control the rudder 25, two stationary solenoids 60 and 61 are arranged coaxially with the valve-stem in such a manner that when either solenoid is energized the valve-stem will be drawn as a core 95 towards that solenoid, and when the solenoid is deenergized the valve-stem 42 will be permitted to return to its normal and central position, as shown in Fig. 1 under the action of the springs 50 and 51.

For energizing the solenoids 60 and 61 selectively a normally vertical shaft 75 is mounted upon the boat or movable body to rotate in an elongated fixed bearing 76 and is provided at its lower end with radial arms 110 78 rigid therewith and the other ends of which are turned downwardly and are inte-

gral with or rigidly secured to a continuous azimuth ring 80 which is coaxial with the shaft 75 and which is arranged in a normally horizontal plane. Secured within this 5 ring but insulated therefrom and from each other are two approximately semi-circular conducting plates 81 and 82 which are slightly spaced apart by diametrically opposed insulating segments 83 and 84, and which are 10 arranged to be slidably engaged over their inner surfaces by a yielding contact or brush 85 carried by the outer end of a normally horizontal arm 90 which is rigidly secured to and insulated from a vertical spindle 91 15 which is arranged in longitudinal alinement with the vertical shaft 75, the arm 90 being provided with a downwardly projecting hub 92 integral therewith and which surrounds the spindle 91 and is insulated therefrom. 20 Slidably engaging this hub 92 is a brush 93 which is connected by a conductor 94 to one pole of a battery 95, the other pole of which is connected by a conductor 96 and branch conductors 97 and 98 to the inner ends of 25 the coils of the two solenoids 60 and 61. The outer ends of the coils of the two solenoids 60 and 61 are connected respectively by conductors 99 and 100 to two stationary brushes 101 and 102 respectively which slidably engage respectively two conducting rings 103 and 104 which are rigidly secured to but insulated from the shaft 75 and which are electrically connected respectively to the 30 two semi-circular segmental conductors 82 and 81 by two conductors 105 and 106, which extend downwardly through but which are insulated from the vertical shaft 75 (see Fig. 6). The vertical spindle 91 is arranged to be held against rotation in space by 35 40 means of a gyroscope 110 or other stabilizing means so as to cause the arm 90 carrying the yielding contact 85 to be pointed always in a fixed direction.

When the azimuth ring 80 is held against 45 rotation with respect to the boat, the gyroscope 110 will act to cause the yielding contact 85 to make engagement with one or the other of the semi-circular conductors 81 and 82 depending upon the direction in 50 which the boat is moving, and by closing the circuit through the corresponding solenoid 60 or 61 will cause the rudder 25 to be turned in such a position as to cause the boat to assume the direction and proceed along the 55 course predetermined by the gyroscope.

For controlling the rotary movement of the vertical shaft 75 and consequently the direction of movement of the boat 19 in response to radiant energy, a flat, circular, 60 horizontal disk 124 of insulating material loosely surrounds the shaft 75 and is held in a fixed position coaxial with the shaft 75 in any suitable manner, as for instance by a fixed bracket 125. Upon the opposite sides 65' of this disk 124 are secured in any suitable

manner two marginal series of insulated conducting segments 126 to 140 and 126' to 140', the segments of one series being arranged respectively vertically opposite corresponding segments of the other series. Rigidly 70 secured to but insulated from the vertical shaft 75 are two conducting brush arms 145 and 146 which extend in the same direction from the shaft 75 and which are spaced respectively above and below the two series of 75 conducting segments 126 to 140 and 126' to 140' respectively. These conducting arms 145 carry at their outer ends respectively two brushes 147 and 148 which are in vertical alinement and which are arranged to 80 engage slidably the two series of conducting segments 126 to 140 and 126' to 140' respectively. The two brush arms move in unison and when one brush 147 is on any given upper segment 126 to 140, the other 85 brush 148 will be on a corresponding lower segment 126' to 140' in vertical alinement with the given upper segment.

The upper series 126 to 140 of conducting segments are connected respectively by conductors 156 to 170 to successive points on a primary variable coil or inductance 175. The lower series of segmental conductors 126' to 140' are connected by the corresponding series of conductors 156' to 170' with 90 successive points of a secondary variable coil or inductance 175' which is inductively coupled to the primary coil 175 and which forms with the primary coil 175 a transformer 179. The upper conducting arm 145 is provided with an annular conducting ring 190 integral therewith and coaxial with and insulated from the shaft 75. Arranged to be 95 slidably engaged by this conducting ring 190 is a brush 191. The lower arm 146 is provided upon its under side with a conducting ring 196 integral therewith and coaxial with but insulated from the shaft 75. A brush 197 is arranged to be slidably engaged by this 100 latter ring 196 and is connected by a conductor 198 to one terminal of a detector of any suitable construction, for instance to the 105 terminal of the filament 199 of a gaseous detector 200 which includes a grid 201 and a top terminal 202, the filament 199 being arranged to be heated by a battery 205 which is connected to the filament through a variable resistance 206. The grid 201 of the detector 200 is connected by a conductor 210 to the outer end of the secondary inductance 110 115 175'. A variable condenser 215 is connected upon one side by a conductor 216 to the conductor 198 leading from the lower brush 197, and is connected upon its other side by a conductor 217 to the conductor 210 leading from the outer end of the secondary coil 175'. The 120 variable condenser 215 as thus connected forms part of a secondary variable closed oscillatory circuit 220 which includes the 125 130

lower brush 197, the lower switch arm 146, and a variable portion of the secondary variable inductance 175', and which is arranged to be tuned successively to various predetermined frequencies depending upon the position of the switch arm 146. 70

For rotating the vertical shaft 75 automatically either in one direction or in an opposite direction, a gear 250 surrounds and is secured to the shaft 75 and is engaged by a pinion 251 which is arranged to be continuously rotated either in one direction or in an opposite direction about a fixed axis by a stationary reversible electric motor 255 which is arranged to be energized by a battery 260 to act alternately through two pairs of conductors 261 and 262 which lead respectively from four brushes 265, 266, 267 and 268 to the motor 255, the battery 260 being connected between the conductors of the pair 262. The brushes 265-268 are arranged to be slidably engaged by a commutator 270 which is rigid with and arranged to be rotated upon a fixed axis upon a shaft 271. The commutator 270 is provided upon its opposite sides respectively with two series of contacts 275, 276, 277, 278 and 275', 276', 277' and 278'. The alternate contacts 275, 277 and 276, 278 of one series of contacts are connected by conductors 279 and 280, while the outer contacts 275', 278' and the two inner contacts 276', 277' of the other series of contacts are connected by conductors 285 and 286.

The construction of the commutator 270 is such that when the commutator is in the position shown in Fig. 1 the circuit will be closed through the battery 260 and motor 255 in such a manner as to rotate the motor 255 in a given direction and so that when the commutator 270 has been rotated through 180° from the position shown in Fig. 1 to that shown in Fig. 3 the circuits will be closed through the battery 260 and the motor 255 in such a manner as to rotate the motor 255 in an opposite direction.

For rotating the commutator 270 step by step through an arc of 180° at each step, a gear 290 is loosely secured to one end of the shaft 271 and is engaged by a rack 295 reciprocated in a predetermined straight path as the result of the energization and deenergization of a solenoid 296. Rigidly secured to the shaft 271 is a ratchet 287 which is operated by a spring pressed pawl 288 pivotally mounted on the gear 290 so as to rotate the commutator 270 through 180° at each reciprocation of the rack 295. One end of the rack 295 forms a core for the solenoid 296 and the rack 295 is normally pressed outwardly from the solenoid 296 by a spiral spring 297 which is arranged between the solenoid 296 and a collar 298 which surrounds and is fixed upon the rack 295. The solenoid 296 is in a normally closed circuit

305 which is arranged to be energized by a battery 306 and to be controlled by a normally closed switch 307 which is arranged to be controlled by a fixed electromagnet 308 which is arranged in a circuit 309 containing a battery 310 and arranged to be controlled by the detector 200.

The arrangement is such that when the detector 200 is not being acted upon by energy received through the secondary coil 175' or a part thereof, the circuit through the solenoid 296 will be closed and the rack 295 will be held in its innermost position with respect to the solenoid 296 against the action of the spring 297, and when an impulse of energy is received by the detector 200, the electromagnet 308 will be energized and will open the circuit through the solenoid 296 thus deenergizing the solenoid 296 and permitting the rack 295 to be pushed outwardly from the solenoid 296 by the spring 297 which will not rotate the commutator 270. When the electromagnet 308 is deenergized the circuit through the battery 306 and solenoid 296 will again be closed and the rack 295 will be moved into its innermost position with respect to the solenoid 296 to give the commutator 270 a rotation through 180° and thus reverse the direction of movement of the motor 255. 95

For receiving radiant energy from a distant station, the receiving system is provided with an open aerial circuit 311 including an antenna 312 which is grounded through a primary coil or inductance 313 as at 314. 100 This open circuit 311 is tuned to the high frequency of the waves which it is designed to receive. The primary coil 313 is inductively connected to a secondary coil 315 which is in a closed oscillatory circuit 316 105 which includes a variable condenser 317 and which is tuned to the same frequency as the open circuit 311. This closed oscillatory circuit 316 is arranged to control any suitable detector, as for instance an evacuated detector 318 comprising an evacuated container 319 in which is arranged a filament 320 and a plate terminal 321. One end of the filament 320 is connected by a conductor 322 to the hereinbefore described brush 191, 110 and the plate terminal 321 is connected by a conductor 323 through a battery 323' to the outer end of the primary coil 175. A variable condenser 324 is connected upon its opposite sides to the two conductors 322 and 323 and as thus arranged forms part of a primary variable closed oscillatory circuit 324', which contains the upper brush 191, the upper switch arm 145 and a variable portion of the primary variable coil 175, and 115 which is arranged to be tuned successively to various predetermined frequencies depending upon the position of rotation of the switch arms 145 and 146, the frequency to which the primary variable closed oscillatory circuit 324' is tuned being controlled by the detector 318. 120

tory circuit 324' is tuned for any given position of the switch arms 145 and 146 being always equal to the frequency to which the secondary variable closed oscillatory circuit 220 is tuned for the same position of the switch arms 145 and 146.

In Figs. 7 to 9 inclusive is shown an improved transmission system constructed in accordance with this invention and particularly adapted to be used in controlling the hereinbefore described receiving system shown in Figs. 1 to 6 inclusive. This improved transmitting system comprises an open aerial circuit including an antenna 325 which has in series therewith a coil 326, and which is grounded in any suitable manner as at 327. This open aerial circuit 325, 326, 327 is tuned to the same frequency as the open aerial circuit 311 of the receiving system shown in Fig. 1. The coil 326 forms the secondary of a transformer 330 having a primary coil 331 which is arranged in a closed oscillatory circuit including a spark-gap device 332 and a variable condenser 335, and which is tuned to cause a maximum oscillation of the open circuit 325, 326, 327. This oscillatory circuit 331, 332 and 335 is arranged to receive energy from any suitable source of direct current, as for instance from a 500 volt D. C. electric generator 340 having one brush 341 connected through a choke-coil 342 and a conductor 343 to one side of the variable condenser 335 and having its other brush 344 connected through a choke-coil 345 and a conductor 346 to the other side of the variable condenser 335.

For producing periodic amplitude variations, variable in a predetermined manner in frequency, in the high frequency radiant oscillations emitted by the open aerial circuit 325, 326, the two conductors 343 and 346 are connected by a tone circuit including a variable condenser 350 and an inductance 351. The variable condenser 350 may be of any suitable construction, but preferably includes a stationary casing 355 made of insulating material having arranged therein a stationary, substantially semi-circular conducting plate 357 which is electrically connected to the inner end of the inductance 351, and having an approximately semi-circular conducting plate 358 which is rigid with but insulated from a rotatable shaft 359 coaxial with the stationary plate 357 and with the casing 355. This movable plate 358 is arranged to be electrically connected at all times in any suitable manner by a conductor 360 to the hereinbefore described conductor 343. The shaft 359 is arranged to be rotated into any desired position in either direction by means of a gear 361 rigid with the outer end of the shaft 359 and which is arranged to cooperate with a suitable gear 362 rigidly secured to a shaft 363 supported 65 in a bearing 363'. The shaft 363 has rigidly

secured thereto a pointer 364 which is arranged to cooperate with suitable equi-spaced graduations 365 upon a stationary dial 366. The graduations 365 upon the dial 366 are equal in number to the number 70 of segmental conductors 126-140 upon one side of the insulating disk 124 of the receiving system (see Figs. 1 and 2), and the variable condenser 350 is so arranged that when the generator 340 is in operation and the pointer 364 is as shown upon a given one of the graduations 365 it will cause the open aerial circuit 325, 326, 327 to transmit electroradiant waves having the same high wave frequency as the high frequency to 80 which the open aerial transmission and receiving circuits are tuned, and having impressed thereon periodic amplitude variations having a frequency determined by the position of the pointer 364 and equal to the 85 frequency to which the primary and secondary variable closed oscillatory circuits 324' and 220 of the receiving system shown in Fig. 1 are tuned when the two switch arms 145 and 146 are positioned as shown so that 90 the brushes 147, 148 carried thereby will be in engagement respectively with a corresponding pair of the oppositely disposed series of segments 126 to 140 and 126' to 140'. 95

The parts are so arranged and proportioned that with the parts in the positions shown in the drawings if the pointer 364 of the transmission system should be rotated in a clockwise direction step by step from one graduation 365 to the next graduation 365 at each step, and if the switch arm 145 were correspondingly and synchronously moved in a counter clockwise direction step by step from one segment to the next segment at each step, then the frequency of the periodic amplitude variations of the emitted waves would be changed step by step and the tuning of the receiving circuit 324 and 220 would be correspondingly changed step by 105 step so as to cause these circuits to be always tuned to the same frequency as and to be responsive to the periodic amplitude variations of the waves received from the transmitting system. 110

In the operation of this improved system, the gyroscope 110 is so adjusted that when the arms 145 and 146 are positioned centrally, as shown in Figs. 1 and 2, the brush 85 carried by the arm 90 controlled by the gyroscope 110 will rest upon the insulation 83 between adjacent ends of the two semi-circular segmental conductors 81 and 82 and the rudder 25 of the vessel will be held in a central position by the springs 37 and 38 to cause the boat to be steered in a straight line extending in the direction of the longitudinal axis of the vessel. The pointer 364 of the transmission system is then set vertically as shown in Fig. 7. The motor 255 of 125 130 135

the receiving system is then permitted to operate continuously while the generator 340 of the transmission system is being operated continuously. When the pointer 364 is thus 5 set in a central position the open aerial transmission circuit 325, 326, 327 of the transmission system will be caused to transmit electroradiant oscillations having a predetermined high frequency the same as the 10 high frequency to which the open aerial receiving circuit 311 is tuned and having impressed thereon periodic amplitude variations having a predetermined frequency the same as the frequency to which the two 15 closed oscillatory receiving circuits 324' and 220 and now tuned.

Now as the open aerial receiving circuit 312, 313, 314 is acted upon by the radiant oscillations, corresponding oscillations having impressed thereon periodic amplitude 20 variations will be set up in the closed oscillatory circuit 316 and these will act through the detector 318 to set up corresponding unidirectional current impulses to flow through 25 the circuit comprising the conductor 323, battery 323', part of coil 175, conductor 160, switch 145, brush 191, conductor 322 and detector 318. These pulsations in the coil 175 will cause corresponding oscillations to 30 be set up in the closed circuit 324' which will act inductively through the coil 175 to set up corresponding oscillations in the closed circuit 220 which will act through the detector 200 to energize the electromagnet 308, thus opening the circuit through 35 the battery 306 and deenergizing the solenoid 296 and thus permitting the rack 295 to be moved outwardly from the solenoid 296 by the action of the spring 297 without 40 affecting the commutator 270.

Meanwhile, under the action of the motor 255 the two arms 145 and 146 will be rotated either in one direction or in the opposite direction until the brushes 147 and 148 carried 45 thereby are moved off of the central segments 130 and 130' and consequently the receiving circuits through the central segments 130 and 130' will be broken and the receiving circuits will be completed say through 50 the next pair of segments 129 and 129'. When this occurs, the receiving circuits 324' and 220 will be thrown out of tune with the period amplitude variations of the electroradiant oscillations which are being transmitted from the transmission system, and consequently the detector 200 will cease to respond and the electromagnet 308 will be deenergized thus permitting the switch 307 to close the circuit through the battery 306 and the solenoid 296 to draw the rack 295 towards the solenoid 296, thus rotating the commutator 270 through half a revolution 55 in a clockwise direction, as viewed in Fig. 4, to reverse the motor 255 and thus to return the arms 145 and 146 into engagement 60

with the segments 130 and 130' respectively to again render the receiving circuits 324' and 220 responsive to the energy received and therefore to again operate the detector 200 to open the circuit through the solenoid 70 296 and consequently to permit the rack 295 to be moved outwardly with respect to the solenoid 296 by the spring 297 but without turning the commutator 170.

The motor 255 after thus having been reversed continues to rotate in the same direction until the brushes 147 and 148 have been rotated into engagement with the next succeeding segments 131 and 131' respectively, whereupon the detector 200 will be 80 deenergized, consequently permitting the switch 307 to be closed by its spring, thus energizing the solenoid 296 and consequently moving the rack 295 towards the left to turn the commutator 270 through 180 degrees to 85 reverse the motor 255 and consequently to move the brushes 147 and 148 back into engagement with the segments 130 and 130' respectively, whereupon the cycle of operations will be repeated periodically in quick 90 succession so as to cause the arms 145 and 146 to be oscillated repeatedly in quick succession through a small arc across the two segments 130 and 130'.

The shaft 75 and the azimuth ring 80 carried thereby will thus be caused to vibrate rapidly through a very small arc and thus be held approximately in a given position with respect to the boat and the boat will be caused to be directed accordingly upon a 100 substantially straight line in a corresponding direction and in a well known manner as a result of the cooperative action of the brush 85 upon the segments 81 and 82 carried by the azimuth ring 80 under the control of the gyroscope 110 and arranged to 105 control the solenoids 60 and 61 and consequently the rudder 25 in a well known manner.

If now it should be desired to divert the 110 vessel either to the right or to the left through one or more degrees, the indicator 364 (see Fig. 6) of the transmission system should be rotated in a suitable direction from its central position through the desired 115 number of degrees. This will change the frequency of the periodic amplitude variations of the transmitted waves accordingly. If, at the time this change in the position of the indicator 364 is made, the switch arms 120 are moving in either direction over the central segments 130, 130', the direction of movement of the switch arms will be reversed, and the arms will then move in the 125 reversed direction until they come into a position of rotation corresponding to the position of rotation of the indicator 364. If, however, at the time this change in the position of the indicator 364 is made, the arms 145 and 146 are not in engagement 130

with the central segments 130 and 130', but are moving in either direction across some other segments, the arms will continue to rotate in the same direction until they come 5 into the position of rotation corresponding to the position of rotation of the indicator 364. When the arms 145 and 146 have reached this position of rotation the closed oscillatory receiving circuits 324' and 220 10 will be completed in such a manner as to be rendered responsive to the changed frequency of the periodic amplitude variations of the waves transmitted by the transmission system and the arms 145 and 146 will 15 thus be caused to oscillate through a small arc across the corresponding pair of segments as hereinbefore described to steer the boat accordingly.

For instance, if when the indicator 364 is 20 in an approximately central position as shown in Fig. 7 to cause the boat to be steered in a straight line as hereinbefore described, if it should be desired to swing the boat for instance through about 45° to 25 the right, the indicator 364 of the transmission system should be moved to about 45° towards the right or in a clockwise direction, and this would cause the transmission system to transmit electroradiant oscillations having impressed thereon periodic amplitude variations having a frequency corresponding to the frequency to which the receiving circuits 324' and 220 would be tuned if the arms 145 and 146 were moved 30 35 toward the left or in a counter-clockwise direction from a central position through about 45° so as to make contact for instance with the corresponding segments 128 and 128'. As the motor 255 is constantly rotating in one direction or in an opposite direction, the arms 145 and 146 would be moving either in one direction or in the opposite direction when this change in the frequency of the periodic amplitude variations of the 40 45 transmitted waves might happen to be effected. If at the time of this change the arms 145 and 146 should happen to be upon the segments 130 and 130' and moving in a clockwise direction, then as a result of the 50 55 change in the frequency of the received waves the arms 145 and 146 would be reversed in movement and would be moved in a counter-clockwise direction, as hereinbefore described, until they came into engagement with the segments 128 and 128', when they would be oscillated across these segments as hereinbefore described. If at the 60 65 time of this change in the frequency of the periodic amplitude variations of the received waves the arms 145 and 146 should happen to be moving in a counter-clockwise direction, the arms 145 and 146 would be immediately reversed and would then continue to move rapidly in a clockwise direction 65 through about 315° until they came into

engagement with the segments 128 and 128'.

If at the time of making this change in the frequency of the periodic amplitude variations of the received waves the arms 145 and 146 should not happen to be moving in either direction over the central segments 130, 130' but should happen to be moving over another pair of segments (except the segments 128, 128') then the arms 145 and 146 would continue to move in the same direction until they came into engagement with the segments 128, 128'.

In any case when the arms 145 and 146 reached the segments 128, 128', the receiving circuits would respond to the received energy to operate periodically the detector 200 to reverse the motor 255 periodically as hereinbefore described to cause the arms 145 and 146 to vibrate through a small arc across the segments 128, 128' and thus be held approximately in a given position making an angle of about 45° with their central position, and causing the rudder 25 to be rotated through the limit of its movement, as hereinbefore described, to divert the boat accordingly until the boat has been rotated towards the right about 45° from its original course, whereupon the rudder would be controlled automatically by the gyroscope 110 as hereinbefore described, to cause the boat to continue upon a substantially straight course making an angle of substantially 45° with its original course.

Although only a single form is shown in which the invention may be embodied, it is to be understood that this invention is not limited to any specific construction but might be embodied in various forms without departing from the spirit of the invention or the scope of the appended claims.

Having thus fully described my invention, I claim:

1. The combination with means for transmitting radiant impulses, including controlling means movable through a variable path and operative to vary the frequency of said impulses from time to time in proportion to the space through which said controlling means is moved, of receiving means including means arranged to be moved through a variable path in response to said impulses as the result of and in proportion to the movement of said controlling means.

2. The combination with means for transmitting radiant impulses, including controlling means arranged to rotate through a variable arc and operative to vary the frequency of said impulses from time to time in proportion to the space through which said controlling means is moved, of receiving means including means arranged to be moved through a variable path in response to said impulses as the result of and in proportion to the rotation of said controlling means.

3. The combination with means for transmitting radiant impulses, including controlling means arranged to swing through a variable arc and operative to vary the frequency of said impulses from time to time in proportion to the space through which said controlling means is moved, of receiving means including means arranged to swing through a variable arc in response to said impulses and as the result of and in proportion to the swinging movement of said controlling means.

4. The combination with means for transmitting radiant impulses, including a controlling element arranged to swing through a variable arc and operative to vary the frequency of said impulses from time to time in proportion to the space through which said controlling means is moved, of receiving means including means arranged to be swung through a variable arc in response to said impulses and as the result of and in proportion to the swinging movement of said controlling element.

5. The combination with means for transmitting electro-radiant impulses, including controlling means movable through a variable path to vary the frequency of said impulses, of a movable body, and receiving means carried thereby and arranged to move said body through a variable path in response to said impulses as the result of and in proportion to the movement of said controlling means.

6. The combination with means for transmitting electro-radiant impulses; including controlling means movable through a variable path to vary the frequency of said impulses, of a movable body, and means carried by said body and arranged to move said body either in one direction or in a contrastive direction in response to radiant energy and as the result of and in proportion to the movement of said controlling means.

7. The combination with means for transmitting radiant impulses, including controlling means movable through a variable path and operative to vary the frequency of said impulses from time to time in proportion to the space through which said controlling means is moved, of a movable body, and receiving means carried by said body and arranged to move said body through a variable path in response to said impulses as the result of and in proportion to the movement of said controlling means.

8. The combination with means for transmitting radiant impulses, including controlling means movable through a variable path and operative to vary the frequency of said impulses from time to time in proportion to the space through which said controlling means is moved, of a movable body, and receiving means carried by said body and arranged to swing said body through a vari-

able path in response to said impulses as the result of and in proportion to the movement of said controlling means.

9. The combination with means for transmitting radiant impulses, including an aerial circuit arranged to emit electro-radiant impulses, and controlling means therefor arranged to swing through a variable arc, of a movable body, and receiving means carried by said body and arranged to swing said body through a variable arc in response to radiant energy and as the result of and in proportion to the arc of movement of said controlling means.

10. The combination with means for transmitting radiant impulses, including an aerial circuit arranged to emit electro-radiant impulses, and controlling means therefor arranged to swing through a variable arc, of a movable body, and receiving means carried by said body and arranged to swing said body through a variable arc in a given plane in response to radiant energy and as the result of and in proportion to the arc of movement of said controlling means.

11. The combination with means for transmitting electro-radiant energy, including an element arranged to swing about a given axis through a variable arc, of a movable body, steering means carried by said body, stabilizing means carried by said body, and receiving means carried by said body and arranged to cooperate with said steering means and said stabilizing means to swing said body through a variable arc in response to radiant energy and as the result of and in proportion to the arc of movement of said controlling means.

12. The combination with means for transmitting electro-radiant energy, including an element arranged to swing about a given axis through a variable arc, of a movable body, steering means carried by said body, stabilizing means carried by said body, and receiving means carried by said body and arranged to cooperate with said steering means and said stabilizing means to swing said body through a variable arc in response to radiant energy and as the result of and in proportion to the arc of movement of said controlling means, said stabilizing means being operative to cause said body to be steered in a direction determined by the angle of rotation of said controlling means.

13. The combination with means for transmitting electro-radiant energy, including an element arranged to swing about a given axis through a variable arc, of a movable body, steering means carried by said body, stabilizing means including a gyroscope carried by said body, and receiving means carried by said body and arranged to cooperate with said steering means and said stabilizing means to swing

said body through a variable arc in response to radiant energy and as the result of and in proportion to the arc of movement of said element.

5 14. The combination with means for transmitting electro-radiant energy, including an element arranged to swing about a given axis through a variable arc, of a movable body, steering means carried 10 by said body, stabilizing means including a gyroscope carried by said body, and receiving means carried by said body and arranged to cooperate with said steering means and said stabilizing means to swing said body through a variable arc in response to radiant energy and as the result of and in proportion to the arc of movement of said controlling means, said stabilizing means being operative to cause 15 said body to be steered in a direction determined by the angle of rotation of said element.

15. The combination with means for transmitting radiant impulses, including 20 controlling means movable through a variable path to vary the frequency of said impulses from time to time in proportion to the space through which said controlling means is moved of the energy transmitted, 25 of receiving means including means arranged to be moved through a variable path in response to radiant energy and as the result of and in proportion to the movement of said controlling means.

30 16. The combination with means for transmitting radiant oscillations, of means for impressing upon said oscillations periodic variations having a variable frequency and including controlling means movable 40 through a variable path to vary said frequency, and receiving means responsive to said oscillations and including means arranged to be moved through a variable path in response to radiant energy and as the result of and in proportion to the movement of said controlling means.

45 17. The combination with means for transmitting radiant oscillations, of means for impressing upon said oscillations periodic amplitude variations having a variable frequency and including controlling means movable through a variable path to vary said frequency, and receiving means responsive to said oscillations and including means arranged to be moved through a variable path in response to radiant energy and as the result of and in proportion to the movement of said controlling means.

50 18. The combination with means for transmitting radiant oscillations, of means for impressing upon said oscillations periodic variations having a variable frequency, including controlling means arranged to be

swing through a variable arc to vary said frequency, and receiving means responsive to said oscillations and including means arranged to be swung through a variable arc as a result of and in proportion to the movement of said controlling means.

55 19. The combination with means for transmitting radiant oscillations, of means for impressing upon said oscillations periodic amplitude variations having a variable frequency, including controlling means arranged to swing through a variable arc to vary said frequency, and receiving means responsive to said oscillations and including means arranged to be swung through a variable arc as a result of and in proportion to the movement of said controlling means.

60 20. The combination with means for transmitting radiant oscillations, of means for impressing thereon periodic variations having a variable frequency, and receiving means responsive to said oscillations and including means movable through a variable path determined by the frequency of said variations.

65 21. The combination with means for transmitting radiant oscillations, of means for impressing thereon periodic amplitude variations having a variable frequency, and receiving means responsive to said oscillations and including means movable through a variable path determined by the frequency of said variations.

70 22. The combination with means for transmitting radiant oscillations, of means for impressing thereon periodic variations having a variable frequency, and receiving means responsive to said oscillations and including means arranged to be swung through a variable arc determined by the frequency of said variations.

75 23. The combination with means for transmitting radiant oscillations, of means for impressing thereon periodic amplitude variations having a variable frequency, and receiving means responsive to said oscillations and including means arranged to be swung through a variable arc determined by the frequency of said variations.

80 24. A receiving system for impulses including a circuit tuned to a given frequency, and means controlled by the received impulses and arranged to be automatically varied in response to variations in the frequency of the received impulses for varying the tuning of said circuits to make the tuning of said circuit correspond to the frequency of said impulses.

85 Signed at New York, in the county of New York and State of New York, this 23rd day of March, A. D. 1918.

JOHN HAYS HAMMOND, JR.
